UNITED STATES PATENT OFFICE.

ANTON E. CARLSON, OF MERCHANTVILLE, NEW JERSEY.

VALVE-GRINDER.

1,401,391.

Specification of Letters Patent. Patented Dec. 27, 1921.

Application filed November 29, 1920. Serial No. 427,173.

To all whom it may concern:

Be it known that I, ANTON EMANUEL CARLSON, Swedish subject, (having declared his intention of becoming a citizen of the 5 United States,) residing at Merchantville, in the county of Camden, State of New Jersey, have invented a new and useful Valve-Grinder, of which the following is a specification.

10 My invention consists of a novel construction of a valve grinder, wherein I employ a casing inclosing the principal operative parts, said casing having one side thereof removable and being provided at its upper 15 and lower portions with bearings for the spindle employed, said spindle having at its upper portion a pinion in mesh with a rack carried by a yoke, said yoke being operated by suitable cam mechanism, whereby the 20 continuous rotation of the outer handle will impart an oscillatory movement to the spindle and its adjuncts.

It further consists of a novel construction 25 of mechanism for transforming the rotary motion of the actuating handle and cam into oscillatory motion, the lower end of the oscillatory spindle being provided with a suitable valve engaging implement, whereby the valve is oscillated upon its seat, according 30 to requirements.

It further consists of other novel features of construction and advantage, all as will be hereinafter fully set forth and pointed out in the claims.

35 For the purpose of illustrating my invention, I have shown in the accompanying drawing, one form thereof which is at present preferred by me, since the same will give in practice satisfactory and reliable results, 40 although it is to be understood that the various instrumentalities of which my invention consists may be variously arranged and organized and that my invention is not limited to the precise arrangement and organization 45 of these instrumentalities as herein shown and described.

Figure 1 represents a side elevation of my novel construction of valve grinder, the cover of the casing being removed.

50 Fig. 2 represents a section on line 2—2 Fig. 1, certain of the parts being shown in elevation.

Similar numerals of reference indicate corresponding parts.

55 Referring to the drawings:—

1 designates my novel construction of

valve grinder, the same comprising a casing or body member 2, in which the operative parts of my invention are contained, said casing at its upper portion carrying the 60 handle member 3, having the hand piece 4. The upper inner wall of the casing contains the seat 5, into which is stepped the end 6 of the spindle 7, on the upper portion of which is pinned the sleeve 8 of the pinion 9, 65 so that the latter and said spindle rotate or oscillate in unison, said spindle and pinion being retained in their proper position by the lower collar 10 pinned to said spindle, said collar bearing on the lower wall 11 of 70 the casing 2.

The pinion 9 is in mesh with the rack or segment 12, which is carried on the top of the yoke 13, the latter being composed of the top 14, which carries the rack 12, the parallel sides 15 and the bottom 16 which oscillates on the pin 17, the latter having a head 18, and its outer end being secured or pinned in the boss 19.

The inner parallel walls 20 of the yoke 13 80 contact with the periphery of the cam member 21, the latter being of the form of a disk eccentrically secured to the pin 22, which is mounted in the boss 23 and seated or pinned in the seat 24 of the handle 25.

85 The operation is as follows:—

As the handle 25 is rotated, the pin 22 and the cam or eccentric member 21 will be continuously rotated and the contact of the periphery of said cam 21 with the walls 20 90 will impart an oscillatory movement to the yoke 13, whereby the rack 12 will oscillate from right to left, thereby imparting an oscillatory movement to the pinion 9, the spindle 7 and its adjuncts.

95 By the provision of the handle 4, the operator can readily exert a longitudinal thrust upon the spindle 7 so as to exert the desired pressure upon the valve during the act of grinding the same upon its seat.

100 By the provision of the seat 5 a stepped bearing is formed in the upper portion of the casing 2, so that the spindle is effectively guided at its upper end 6 and at its intermediate portion where it has its bearing in 105 the lower portion of the casing 2.

The collar 10 retains the spindle and pinion 9 and their adjuncts in the proper position with relation to the rack 12 and the yoke 13 is at all times properly positioned 110 during its oscillatory movement by reason of the head or flange 18 on the pin 17.

Upon the removal of the plate or closure 26, all the parts are readily accessible, as will be understood from Fig. 1, for the purpose of inspection, replacement or repairs, 5 and upon the removal of the transverse pin which secures the pin 22 to the handle and the removal of the transverse pin which secures the pin 17 in its boss, all the parts are readily accessible in case it is desired to 10 replace any of the same.

The blade or implement 27 at the bottom of the spindle 7 is provided with the projections 28, which are adapted to engage the valve, and it will be apparent that the plate 15 or implement 27 can be used in the position seen in Figs. 1 and 2, or, if desired, it can be reversed and the projection 28 caused to engage the valve or other member to be ground or oscillated. The implement 27 is 20 held in its desired position by means of the flat spring 29 having a pin 30 thereon, which is adapted to engage the holes 31 or 32, according to requirements.

It will be apparent from the foregoing 25 that I have devised a novel construction of valve grinder, which will be cheaply manufactured and will be durable and effective under all conditions, and which is not liable to readily get out of order.

30 It will now be apparent that I have devised a novel and useful construction of a valve grinder, which embodies the features of advantage enumerated as desirable in the statement of the invention and the above 35 description, and while I have in the present instance shown and described a preferred embodiment of it which will give in practice satisfactory and reliable results, it is to be understood that the same is susceptible of 40 modification in various particulars without departing from the spirit or scope of the invention or sacrificing any of its advantages.

Having thus described my invention, what

I claim as new and desire to secure by Letters Patent, is:—

1. In a valve grinder, a casing, a removable plate at one side thereof, a spindle having its upper end stepped into the upper portion of said casing and its intermediate portion rotatably mounted in the lower portion of said casing, a pinion on the upper end of said spindle, a yoke pivotally supported at its lower end in the lower portion of said casing, a cam member eccentrically mounted on a rotary pin journaled in said casing, a 45 rack on the upper end of said yoke engaging said pinion, and a handle connected to said pin for continuously rotating the latter, thereby imparting oscillatory motion to said spindle.

2. In a valve grinder, a casing, a spindle having its upper end provided with a bearing in the upper portion of said casing and its intermediate portion rotatably mounted in the lower portion of said casing, a pinion 50 on the upper end of said spindle, a yoke pivotally supported at its lower end in the lower portion of said casing, and provided with internal parallel walls, a cam member within said casing and having its periphery 55 engaging said parallel walls, a rotary pin on which said cam member is eccentrically mounted, said pin being journaled in said casing, a rack on the upper portion of said yoke engaging said pinion, a collar on said 60 spindle adapted to engage the lower portion of said casing, and thereby to retain said pinion in mesh with said rack, and a handle connected to said pin for continuously rotating the latter and said cam member, thereby 65 imparting oscillatory motion to said spindle.

ANTON E. CARLSON.
